UNITED STATES PATENT OFFICE

2,083,186

FAN

Edward L. Anderson, Detroit, Mich., assignor to
 American Blower Corporation, Detroit, Mich.,
 a corporation of Delaware

Application March 23, 1936, Serial No. 70,198

5 Claims. (Cl. 230—114)

My invention relates to fans and in particular to a method of controlling the volume of air discharged by a fan.

It is a further object to provide a means of 5 directing the air entering the fan to impart to it a preliminary whirl.

In particular it is the object of the invention to provide a conical inlet having annular portions, in which annular portions are mounted the 10 air controlling and guiding vanes.

It is a further object to provide the combination of a Venturi throat and an annular inlet portion of constant diameter in which are located the air controlling and guiding vanes.

15 It is a further object of the invention to provide such an arrangement either with or without a conical air inlet passageway for progressively decreasing the area of the air inlet as the air progresses towards the rotor of the fan.

20 Referring to the drawings, Figure 1 is a section through the rotor and casing of the fan and through the inlet passageway and hub of the air controlling vanes.

Figure 2 is an end elevation from the inlet 25 end taken in section on the line 2—2 of Figure 1 looking in the direction of the arrows. The casing is partially broken away.

Figure 3 is a view similar in section to Figure 1 but with the air controlling and guiding vanes 30 located on the outer end instead of the inner end of the inlet passageway.

Figure 4 is a side elevation of the entrance side of the construction shown in Figure 3 with the casing partially broken away.

35 Referring to the drawings in detail, it constitutes a casing having an air outlet 2 and an air inlet passageway comprising a conical portion 3, a cylindrical portion 4 and a Venturi portion 5. The lip 6 of the Venturi portion extends within but spaced from the rotor of the fan and is arranged parallel to the ring 7 of the rotor. This ring 7 is mounted upon the usual arcuate fan blades 8 mounted upon the back plate 9 that in turn is supported by the hub 10 on the 40 drive shaft 11. The drive shaft 11 is supported in a bearing bracket 12. The shaft is driven by any suitable source of power.

Within the cylindrical section of the inlet passageway as at 4 is mounted a plurality of air 50 controlling and guiding vanes 13 supported at their inner ends upon a hollow hub 14. This hub may or may not be closed, and the closure streamlined as desired. The hub 14 is supported on the radially disposed pivot pins or pintles of

the vanes 13; this reduces drag or resistance by making possible the omission of struts or tie rods.

The axles 15 supporting the vanes 13 extend to a point outside of the cylindrical portion 4 of the inlet casing. On the ends of each of these axles 15 are beveled pinions 16 engaging with the beveled ring gear 17 which can be actuated by the handle 18. The ring gear 17 is mounted on a guide member 19. The exact construction of the actuating mechanism for these blades is not material in its details and may be varied. The controls may be by hand or by automatic machinery.

The positioning of the vanes 13 controls the volume of air delivered by the rotor of the fan. 15 The vanes also impart a preliminary whirl to the air and facilitate the handling of it by the rotor.

In Figures 3 and 4, the cylindrical portion of the air inlet passageway is placed at the inlet of the fan. Otherwise the construction is the same 20 and the adjustment of the vanes is the same.

By providing a cylindrical passageway in which the vanes are mounted, I thereby provide a passageway of constant area in order that the effect upon the air of different positions of the 25 vanes will not vary due to any variation in the diameter of the passageway but the variation in air volume and direction will solely depend upon the position of the vanes.

It will be understood that I desire to comprehend within my invention such modifications as may be necessary to adapt it to varying conditions and uses.

Having thus fully described my invention, 30 which I claim as new and desire to secure by Letters Patent, is:

1. In combination, a blower having a casing and a rotor, an air inlet passageway comprising a cylindrical section and a plurality of vanes mounted for pivotal adjustment about radial co-planar axes in said cylindrical section, a conical section in continuation of the cylindrical section for guiding and directing the air with respect to the vanes, and a Venturi shaped section for guiding the air from the vanes into the rotor of 45 the fan.

2. In combination, in a blower, of a blower casing, a rotor, an inlet tube for incoming air comprising a conical section, a cylindrical section and a Venturi shaped section, and a plurality of vanes adjustably mounted to pivot about radial co-planar axes in said cylindrical section.

3. In combination, in a blower, of a blower casing, a rotor, an inlet tube for incoming air 50

comprising a conical section, a cylindrical section and a Venturi shaped section, and a plurality of vanes in said cylindrical section adjacent the inner end of the inlet passageway and adjustably mounted to pivot about radial co-planar axes.

4. In combination, in a blower, of a blower casing, a rotor, an inlet tube for incoming air comprising a cylindrical section, a conical section and a Venturi shaped section, and a plurality of 5 adjustable vanes disposed wholly within said

cylindrical section adjacent the outer end of the inlet passageway.

5. In combination, a blower having a casing and a rotor, an extended inlet passageway of decreasing diameter comprising a conical section and a cylindrical section, a plurality of adjustable vanes in said cylindrical section, and a Venturi section on the opposite side of the cylindrical section from the conical section. 5

EDWARD L. ANDERSON. 10
